GEORGE STEWART VIVIAN, OF GOLDCERS GREEN, LONDON, ENGLAND.

PERPETUAL CALENDAR.

Application filed July 3, 1922. Serial No. 572,479.

To all whom it may concern:

Be it known that I, GEORGE STEWART VIVIAN, subject of the King of Great Britain and Ireland, residing at Clovelly, The Vale, 5 Golders Green, London, England, have invented a new and useful Perpetual Calendar, of which the following is a specification.

This invention relates to improvements in perpetual calendars of the kind comprising 10 a casing provided with rollers on which are wound sheets or strips carrying the date indications, the figuring being brought to the required positions to indicate the date by rotation of the rollers.

15 The object of the present invention consists in an improved and simplified construction of apparatus of this type which will be easy to manipulate and which enables the date at any given time to be read 20 off expeditiously.

According to the invention, the apparatus comprises an enclosing casing in which are mounted a series of rollers located parallel with one another and each 25 adapted to be rotated by a knob or handle located outside the casing.

Within the casing are mounted two sheets or strips one of which consists of an endless band mounted movably on supporting 30 guides and having numerical indications of the days of the month, whilst the other consists of a strip of appropriate length and of transparent or semi-transparent material which is provided with a series of windows 35 at appropriate points which co-operate with the markings on the first sheet or strip and with a series of markings constituting the days of the week, the latter markings being mounted at one side of the casing and 40 secured to or printed on a stationary portion of the device.

The numerical markings on the date sheet are arranged so that the first numeral of the series may be brought opposite to any 45 of the days of a week on the stationary indicator the remaining numerals being located in rows in the proper sequence as is usual with calendars, whilst the transparent sheet or strip is provided with windows 50 arranged in two sets, one of the sets registering with the markings of the stationary indicator and the other windows co-operat-

ing with the numerals in each of the columns of the movable numerical indicator, so that by intermittent movement of the transparent 55 sheet, in one direction the successive days of the weeks and day in the month can be correctly indicated and seen at a glance.

The date sheet is preferably mounted on a stationary block or carrier fixed within 60 the casing and provided at its upper and lower ends with rounded guides or rollers over which said sheet passes, whilst the transparent apertured sheet is carried by rollers at or towards the top and bottom of 65 the casing the said sheet being located between the front stretch of the date sheet and the glazed front of the casing, and the transparent sheet is adapted to be wound onto one of the rollers and off the other 70 according to which is rotated. By this means the apertured transparent sheet may be moved in front of both the stationary strip giving the days of the week and the date strip which is itself movable. 75

Suitable means are provided for maintaining the movable sheets or strips in the stretched positions as will be hereinafter more fully described.

In order that the invention may be readily 80 understood reference is made to the accompanying drawings which show a calendar constructed according to my invention.

Figure 1 is a front elevation.

Figure 2 is a side elevation.

Figure 3 is a rear view showing the back 85 of the casing partly opened.

Figure 4 is a vertical section with the back of the casing removed.

Figure 5 is a rear view and Figure 6 a 90 side view of the carrier for the sheet or strip carrying the numerical indications removed from the casing.

Figure 7 is a rear view of the transparent sheet or strip and the rollers carrying the 95 same both removed from the casing, and

Figure 8 is a perspective view of the carrier for the month indicating cards.

The apparatus comprises an outer substantially rectangular enclosing casing 10, 100 the rear of which is closed by a slidable plate 11 having pivoted thereto a strut 12 formed of wire or other material by means of which the casing may be made to stand

on a table or other surface as shown in Figure 2. The front of the casing is provided with a glass window 13, at the back of which and to one side is mounted the 5 stationary indicator 9 for the days of a week, such as Sunday, Monday, Tuesday and so on arranged in a vertical column.

Mounted centrally within the casing is a carrier 14 preferably formed from wood or 10 sheet metal, the upper and lower edges being curved rearwardly and inwardly at 15, and 16, whilst when the carrier is formed from sheet metal, the sides are bent rearwardly at right angles to snugly fit between 15 the sides of the casing 10.

Mounted centrally on the carrier is a roller or rod 19 which extends through side walls of the casing, one end of the roller having an operating knob or the like 20. 21 is 20 a sheet or strip formed of flexible material, on the front of which are printed in columns the numerical indications of the days of the month, the first column having the numbers 1 to 7, the second column having the numbers 25 2 to 14 of which the numbers 8 to 14 inclusive come opposite to the numbers 1 to 7 inclusive of the first column, the third column having the numbers 9 to 21 located opposite to the numbers 8 to 14 in the second 30 column, the fourth column having the numbers 16 to 28 arranged relatively in a similar manner, whilst the fifth column has the numerals 23 to 31 located opposite to the numerals 16 to 24 of the fourth column. The 35 sixth column contains the numerals 30 and 31 respectively located opposite to the numerals 23 and 24 of the fifth column. The upper and lower portions of the glass front of the casing are covered by strips 22 and 40 23 of opaque material so spaced apart that only a maximum of seven figures in any column is visible.

Attached at each end to rollers or rods 24, 25 respectively is a sheet or strip 26 of transparent or semi-transparent material, and this strip is provided along one side with a series of windows spaced apart in the manner hereinafter described. The transparent strip 26 passes across the front of both the 50 stationary indicator 9 and the sheet or strip 21 with the numerical markings. The portion of the strip 26 which passes over the indicator 9 is provided with windows 27, and these windows are spaced apart on the strip 55 26 so that only one of them can be visible at any one time from the front of the casing. Opposite the windows 27 are a further series of windows similarly formed and indicated at 28, and these windows 28 are offset with 60 respect to one another in a transverse direction, the distance horizontally between any two adjacent windows 28 of the series corresponding to the distance between the vertical columns of figures on the indicator 65 strip 21.

The rods or rollers 24 and 25 are each extended through the casing 10 and each is provided with a knob or button 30.

These knobs or buttons and also the knob or the like 20 on the end of the rod or roller 19 are constructed in the following manner. The ends of the rods are provided with a recess around the periphery of which is formed two tongues or the like located at diametrically opposite points. The knob 75 proper is provided on its inner side with a recess of a size to snugly fit onto the end of the rod, and the bottom of this recess is provided with an inwardly extending flange or lip 31 provided with diametrically oppositely disposed holes into which the tongues on the end of the rod project so that when the knob is in position the rod is locked thereto and rotates therewith. The knob is thus secured in position by a screw 32 the 80 head of which takes its seating on the inner periphery of the flange within the knob and screws into a screw threaded recess in the end of the rod. The head of the screw 32 is thus located within a recess 33 on the outer 90 side of the knob, which recess is closed by a screw-threaded plug 30a.

The rod 19 by means of which the date sheet or strip 21 is manipulated, carries two rollers or the like 34, each provided on its 95 periphery with a rubber covering which is preferably corrugated or roughened in any suitable manner. The rear stretch of the date sheet 21 is resiliently pressed outwardly towards the rollers 34 by means of a springy 100 plate 36, the upper and lower edges of which are secured to the carrier 14 as shown in Figures 4 and 6, so that the portion of the plate 36 between its upper and lower edges is normally curved where it passes the rollers 105 and thus frictionally holds the rear stretch of the date strip into driving contact therewith.

The outer face of the rear stretch of the date strip is also supported by a springy 110 plate 37, Figures 4, 5 and 6, the central portion of which is provided with upstanding lugs 38 which are threaded onto the rod 19 and serve as distance pieces between the rollers 34, the upper and lower edges of the 115 plate 37 resiliently pressing the rear stretch of the date strip towards the curved portions 15 and 16 respectively of the carrier 14 as shown clearly in Figure 6.

The ends of the transparent apertured strip 26 may be secured to the rollers or rods 24, 25 respectively in any appropriate manner, but in the preferred construction the ends of the rollers are provided with roughened surfaces or grooves as at 40, 40 and 120 after passing the end of the transparent strip round said roller, clips 41 are attached which are formed of spring steel and extend round the rods to substantially three quarters of its circumference so that the 130

strip is firmly secured to the rods and will not readily become detached therefrom if either of the rollers 24, 25 are unnecessarily turned beyond the predetermined limits.

5 The carrier 14, and the rods 19, 24 and 25 are preferably mounted in side members 42, 42 which are fixed to the inner longitudinal side walls of the casing 10 by screws 43.

10 The upper ends of these strips are adapted to form a support for a hinged or removable carrier 45, which is provided on its front face with a receptive chamber 46, open at its front to receive one or more removable and preferably reversible cards marked with the 15 months of the year, one of said cards being shown at 47. The open front of the carrier normally lies against the glass front 13, and is shaped at its top to form a pair of bent springy tongies 48 which when the sliding 20 back 11 is slid into position engage the inner surface of said back and is thereby retained in the proper position. By this means when the month is to be altered, it is merely necessary to slightly open the back 25 as shown in Figure 3, and by tilting or swinging the carrier 45 rearwardly the foremost card may be reversed or changed as desired to bring the proper card into position when the back is again closed.

30 The apparatus operates as follows:— The transparent strip or sheet 26 is first wound completely onto the roller 24. The roller 19 is then rotated to bring the numeral "1" immediately opposite the particular day of the week on which the first day of the particular month falls. The calendar is now set for the month. The roller 25 is then rotated to bring the first window of the series marked 27 to render the particular 35 indication of the day in the indicator 9 visible whilst the window 28 opposite to this window 27 will come opposite to the figure indicating the day of the month. The transparent sheet 26 is subsequently moved forwardly through the distance of one figure for each day and by this means the co-operating windows 27 and 28 will in each case successively indicate both the day of the week and the day of the month throughout 40 the entire month, it being merely necessary to set the indicator strip 21 and to return the transparent strip 26 to the roller 24 at the end of each month.

45 The calendar can thus be set for any month in any year to give the correct indication of the date. Furthermore the day of the week and the day of the month are distinctly marked or lined out by the registering windows 27 and 28 so that the date can be easily 50 and quickly read off even at a distance.

I claim:—

1. A perpetual calendar of the kind set forth, comprising an endless movable band mounted on a carrier fixed within an outer 65 stationary casing and having indications

thereon of the days of the month arranged in columns, means for moving said band on said carrier, a transparent strip mounted between said band and the front of the casing, rollers supporting said strip, markings 70 on said strip co-operating with said band, means for operating each of said rollers supporting said strip independently, and a stationary indicator within the casing and marked to represent days of a complete 75 week, for the purposes set forth.

2. A perpetual calendar, comprising a casing, a stationary indicator provided with markings representing the days of the week, a carrier, a movable endless band mounted 80 on said carrier and having markings arranged in columns representing the days of the month, a roller for moving said band on its carrier, means for rotating said roller, a transparent strip mounted movably between 85 said stationary indicator and movable band and the front of the casing, a pair of rollers on which said strip is supported, means for rotating said rollers independently, and a movable carrier within said casing adapted 90 for the reception of a card indicating the month of the year, for the purposes set forth.

3. A perpetual calendar, comprising a casing, a stationary indicator provided with markings representing the days of the week, a carrier, a movable endless band mounted 95 on said carrier and having markings arranged in columns representing the days of the month, a roller for moving said band on its carrier, means for rotating said roller, a transparent strip mounted movably between 100 said stationary indicator and movable band and the front of the casing, a pair of rollers on which opposite ends of said transparent strip may be wound and unwound, and means for rotating said rollers independently. 105

4. A perpetual calendar comprising a casing, a stationary indicator provided with markings representing the days of the week, a carrier, a movable endless band mounted 110 on said carrier and having numerical indications thereon in columns representing the days of the month, means for moving said band, a transparent strip mounted on a pair of rollers supported for rotation in 115 said casing, apertures in said strip co-operating with the markings on the stationary indicator and the numerals on said movable band, and means for moving said strip by means of said rollers, for the purposes set forth.

5. A perpetual calendar comprising a casing, a stationary indicator provided with 125 markings representing the days of a week, a carrier fixed within said casing, a movable endless band mounted on said carrier, and having markings therein arranged in column formation and representing the days 130

of the month, means for moving said band, a transparent strip mounted between said indicator and movable band on the one hand and the front of the casing on the other hand, a pair of rollers mounted in said casing onto which the ends of the strip may be wound and unwound, and means for rotating each of said rollers independently, for the purposes set forth.

10 6. A perpetual calendar comprising a casing, a stationary carrier fixed within said casing, a stationary indicator mounted on one side of said carrier and provided with markings representing the days of the week, 15 a movable endless band mounted on the other side of said carrier and provided with numerical markings representing the days of the month, means for moving said band, a transparent strip located between said indicator and endless band on the one hand and the front of the casing on the other hand, rollers adapted to support each 20 end of said strip, and means for independently rotating said rollers to wind one end 25 of strip onto one roller and the opposite end of said strip off the other roller, for the purposes set forth.

7. A perpetual calendar comprising a casing, a stationary carrier fixed within said 30 casing, a stationary indicator mounted on one side of said carrier and provided with markings representing the days of the week, a movable endless band mounted on the other side of said carrier and provided with 35 numerical markings representing the days of the month, means for moving said band, a transparent strip located between said indicator and endless band on the one hand and the front of the casing on the other 40 hand, windows in said strip arranged in sets, one set of windows co-operating with the markings in the stationary indicator and the other set of windows co-operating with the markings on the endless band, 45 means for supporting the ends of said strip and means for moving the same with relation to the stationary indicator.

8. A perpetual calendar comprising a casing, a stationary carrier fixed within said 50 casing, a stationary indicator mounted on one side of said carrier and provided with markings representing the days of the week, a movable endless band mounted on the other side of said carrier and provided 55 with numerical markings representing the days of the month, means for moving said band, a transparent strip located between said indicator and endless band on the one hand and the front of the casing on the 60 other hand, windows in said strip arranged in sets, one set of windows co-operating with the markings in the stationary indicator and spaced apart in column formation, and the other set of windows co-operating 65 with the markings on the endless band and

spaced apart and laterally displaced with respect to one another, means for supporting the said strip, and means for moving the same with relation to both the stationary indicator and the endless band.

9. A perpetual calendar comprising a casing, a stationary carrier fixed within said casing, a stationary indicator mounted on one side of said carrier and provided with markings representing the days of the week, 70 a movable endless band mounted on the other side of said carrier and provided with numerical markings representing days of the month, means for moving said band, a transparent strip located between said indicator and endless band on one hand and the front of the casing on the other hand, rollers mounted rotatably in said casing around which the ends of said strip are wound, means for securing the ends of the strip to 75 said rollers, and means for operating each of said rollers independently to move the strip with relation to the stationary indicator, for 80 the purposes set forth.

10. A perpetual calendar of the kind set 90 forth, comprising a casing, a stationary indicator mounted within said casing and having markings representing the days of the week, a carrier within said casing, a movable endless band mounted on said carrier 95 and adjacent said indicator, a roller rotatably mounted in said casing, means for resiliently pressing the rear stretch of said endless band into driving engagement with said roller, means for rotating said roller, 100 markings on said endless band indicating the days of the month, a transparent strip mounted movably between said indicator and band on the one hand and the front of the casing on the other hand, rollers for supporting said strip and means for rotating each of said rollers independently to move 105 said strip, for the purposes set forth.

11. A perpetual calendar of the kind set forth, comprising an outer casing, a carrier 110 mounted within said casing, a stationary indicator having markings thereon representing the days of the week, a movable endless band mounted on said carrier and having markings arranged in columns and representing numerically the days of the month, a roller mounted rotatably towards the centre of said carrier, means for pressing said endless band into driving engagement with said roller, a pair of rollers mounted in said casing, a transparent apertured strip movably mounted between said indicator and band on the one hand and the front of the casing on the other hand, and supported by said rollers, means for rotating said rollers independently and a carrier at the top of the casing having a receptive chamber for removable cards marked to indicate the months of the year, for the purposes set forth.

GEORGE STEWART VIVIAN.
